(57) CLAIM

The ornamental design for a nursing cap as shown and described.

DESCRIPTION

FIG. 1 is a right side elevational view of a nursing cap showing my new design.

FIG. 2 is a bottom plan view thereof.

FIG. 3 is a perspective view thereof.

FIG. 4 is a top plan view thereof; and,

FIG. 5 is a cross-sectional view thereof along line 5-5 in FIG. 4.

The broken lines in the drawings illustrate portions of the nursing cap that form no part of the claimed design.

1 Claim, 5 Drawing Sheets
